(57) **CLAIM**

The ornamental design for a cutting plotter as shown and described.

DESCRIPTION

FIG. 1 is a first perspective view of front, top and right side of a cutting plotter showing our new design;
FIG. 2 is a second perspective view of front, top and left side thereof;

FIG. 3 is a third perspective view of rear, top and left side thereof;

FIG. 4 is a fourth perspective view of rear, top and right side thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

1 Claim, 9 Drawing Sheets
